APPARATUS FOR DRYING MATERIAL.

Application filed April 8, 1922. Serial No. 550,644.

This invention relates to apparatus for drying materials.

An object of the invention is to provide an apparatus for economically and rapidly drying materials such, for example, as last blocks. The invention will best be understood by referring to the accompanying drawings which disclose, merely for illustrative purposes, one embodiment of apparatus for carrying out the invention, wherein:

Fig. 1 is a sectional plan view of the apparatus;

Fig. 2 is a transverse vertical section thereof; and

Fig. 3 is a section taken longitudinally through the base of the apparatus substantially on the line 3—3 of Fig. 1.

The present invention contemplates the production of an apparatus for drying materials such for example as last blocks and clay products by the careful control of the temperature upon all sides of a mass of the material whereby one section of the mass may have a greater or less application of heated or cooled drying medium relatively to other sections to insure the uniform drying of the entire mass and to prevent waste due to improper treatment of one section or another of the mass. To these ends the invention involves a casing 1 having an outer wall 2 composed of any suitable material and an inner wall 3 extending entirely around the interior of said outer wall so as to form insulating compartments or chambers 4, 5, 6 and 7 respectively constituting the four walls of the apparatus, said chambers being separated from each other by suitable partitions such as shown at 8. The inner walls may likewise be formed of any suitable material but preferably they are composed of two layers of sheathing as indicated at 9 and 10 which are separated by a layer of some appropriate moisture-proof substance 11.

The inner walls 3 in the present example extend only part way up as shown at 12, although the invention is not limited to this arrangement the spaces between said inner wall and the outer wall being also terminated and closed by horizontal partitions 13 extending entirely around the casing.

The dimensions of the casing 1 may obvi-

ously be varied to accord with the particular purpose for which it is to be used or to accord with the capacity desired. In the present example the casing is shown as of a size sufficient to enclose a small pile of lasts or other material such as are shown in dotted lines at 14. The top of the casing 1 is herein shown as consisting of a slanting roof 15 and arranged near the peak thereof in the front wall of the casing is a pivoted door 16 pivoted at its lower edge to be opened outwardly to permit the escape of the vapor rising from the material that is being dried within the casing.

By providing the double or chambered side walls of the casing as hereinbefore described the material that is being dried will not be exposed to uneven atmospheric conditions, in fact the spaces between the inner and outer walls will form insulating regions which prevent one side or section of the material from drying more rapidly than another when the latter section of material faces a side of the casing against which a strong wind may be blowing or which side may be colder than another by reason of the fact that the sun is not shining thereon. Furthermore said double walls, by providing such insulating regions, will eliminate condensation forming upon said inner walls which, if permitted to take place, would result in lowering the temperature of the portions of the material that is being dried which are near to said walls while that portion within the center of the pile would not be at all affected by such lowering of the surrounding temperature.

To still further insure the elimination of chilling effects upon the exterior of the casing acting through the side walls thereof means are provided for tempering the contents of the chambers 4, 5, 6 and 7 independently of each other to the end that the face of the material within the casing which faces toward the side thereof against which a strong cold wind or a warm wind may be blowing or upon which the sun may be shining will not vary or be exposed to any different temperature than are any of the other faces of said pile of material. These tempering means consist of pipe lines 17, 18, 19 and 20 connected respectively with any suitable source of heat such as a steam pipe 21

and extending respectively into or through the chambers 4, 5, 6 and 7, valves 22 being arranged in said pipe lines respectively to open or close communication between said pipe lines and the supply pipe.

There may be times, however, when the temperature is higher at one side of the casing than it should be and instead of increasing the temperature of the other side 10 to correspond with the high temperature it is preferable to reduce the excessive temperature so that it will more nearly conform with the lower temperature of the other side. To this end the pipe lines 17, 15 18, 19 and 20 are provided with connections to a brine supplying pipe 23, valves 24 being interposed between said pipe lines and said brine pipe 23 for opening or closing communication therebetween. The 20 blocks of material to be dried are placed or supported upon a perforated floor 25 having perforations 26 placed at suitable distances apart through which a drying medium may be supplied to the blocks piled 25 thereabove.

Obviously the temperature of the drying medium will vary from hot to cold during the drying operation,—consequently means are provided to supply a cold drying medium, a hot drying medium or a drying medium varying in temperature from hot to cold. The hot drying medium is preferably applied through a series of especially constructed steam supplying means which 30 are arranged beneath the perforated floor 25 within a chamber 27, said means preferably consisting of two elongated square headers 28 and 29 arranged one above the other preferably one resting upon the other, 35 the lower one being supported along the bottom of the chamber 27. The headers 28 and 29 extend preferably transversely of the chamber 27 and at one end of the casing, one of these headers constituting the 40 intake and the other the discharge for the heating coils. Communication is provided 45 between the headers 28 and 29 herein by two substantially horizontal series of pipe 30 and 31 extending lengthwise of the chamber 27, the series 30 being connected with the header 28 while the series 31 is connected with the header 29. The pipes of the series 30 are connected by means of elbows 32 with the pipes of the series 31. 50 The distance from the center of the header 28 to the center of the header 29 with which centers the axes of the pipes of the series 30 and those of the series 31 respectively intersect is greater than the distance between the centers of the pipes of said series 55 at the ends that are joined together by the elbows 32. Consequently the two series of pipes will not be exactly parallel but instead the pipes of the series 30 will incline 60 downwardly slightly from the header 28

and a similar inclination will be given to the pipes of the series 31. Hence any water that may result from condensation of steam will have free passage from the upper header to the lower header and not be trapped 70 by said pipes. Supports 33 and 34 are provided at suitable intervals along said pipes to maintain them at the desired angles.

As soon as the air or drying medium whatever its character is heated by the 75 steam within the pipes of the series 30 and 31 it will pass upwardly through the openings or perforations 36 into contact with the blocks piled upon the perforated floor 25. Also considerable heat will be radiated 80 or transmitted to the surfaces or materials above the steam pipes to said blocks and to supply a drying medium to take the place of that which is heated and carried upward through the perforations in the bottom 25 85 to the blocks thereabove I herein provide air ducts, 35, 36, 37 and 38 communicating at various points with the chamber 27. These air ducts are connected outside of the casing with a header 39 which receives its 90 supply of air at two separated points 40 and 41 from a common blower 42. Each of the air ducts 35, 36, 37 and 38 is provided with a damper 43 whereby the supply of air to that duct may be cut off irrespective of the 95 others. The blower 42 may obviously receive its supply of air directly from the atmosphere but in view of the fact that it is often desirable to vary the degrees of 100 temperature of the drying medium means are provided for tempering the air before it reaches the blower and as an example of such means I have shown two air ducts 44 and 45 which unite at 46 to connect with the blower 42.

Air to the duct 44 is provided through a chamber 47 preferably containing coils of steam pipe 48 in communication with the main steam supply pipe 21, a valve 49 being provided to regulate or entirely cut off the supply of steam to said chamber 47. The duct 45 receives its supply of air through a casing 50 within which are coils 51 connected with the main brine pipe 23, a valve 52 being arranged between the coils 51 and the air pipe 23 so as to regulate or entirely shut off communication therebetween. Dampers 53 and 54 are provided in the pipes 44 and 45 respectively whereby hot and cold air in the desired proportions may be admitted to the blower 42 for conveyance to the chamber 27.

The heating instrumentalities, or more correctly, the instrumentalities for tempering the drying medium are sufficient to 125 completely dry the blocks within the drying chamber but naturally with these alone a much longer time will be required to dry the entire mass for invariably the lower portion of the mass will be dried first and 130

some parts, owing to the difficulty in transmitting the heat to all parts uniformly, will be injured during the drying operation so that considerable loss will result.

- 5 During the first stages of drying when the material contains considerable moisture the temperature of the coils within the compartment 27 must be considerably higher than that required for the material itself
 10 in order to produce the desired result but as the moisture of the blocks is removed the temperature of the material will gradually increase or more nearly approach the temperature of the drying medium and the
 15 drier the material becomes the more nearly perfect the same becomes as a medium for transmitting the heat to the material thereabove.

It is desirable to surround or to subject
 20 the material that is to be dried to the action of a tempered fluid of relatively lower temperature than that of the fluid emanating from the chamber 27 and because this cooler fluid which will be referred to as the tempering fluid, has a tendency to settle, it is preferable to admit such at a point or points near the top of the casing or near the top of the pile of material therein—thus to insure a more through contact with all of the
 30 material. The supplying of said cooler fluid to the casing may be effected in numerous ways for example in Fig. 1 are shown partitions 53' and 54' arranged along opposite sides of the casing at predetermined
 35 distances from the inner walls 3. At the bottom of the spaces formed between the partitions 53' and 54' and the adjacent inner walls of the casing are placed ducts 55 and 56 respectively, each having perforations 57 distributed throughout the length to insure a uniform distribution of the fluid into the passages formed by the partitions 53' and 54'.

The ducts 55 and 56 extend through the
 45 wall of the casing and connect with the header 39 hereinbefore referred to from which said ducts receive tempered air or other suitable fluid, the temperature whereof is varied to suit the particular purpose
 50 for which it is to be employed, by the operation of dampers 53 and 54 in the pipes 44 and 45. Dampers 58 and 59 are arranged near the outer end of the header 39 and may be operated to cut off the supply of
 55 tempered air or fluid to one or the other or both of the ducts 55 and 56.

In drying green or wet material a vapor is often produced within the casing which creates a heavy blanket through which it
 60 is difficult to force the drying medium to carry the moisture from the casing. To prevent this blanket of moisture from retarding the drying operations, the partitions 53' and 54' are extended to different
 65 heights—for example the partition 53' ex-

tends only to about $\frac{1}{3}$ the height of the portion of the casing containing the material to be dried and therefore, during the starting of the drying of green or wet material the hot drying material may be admitted through the chamber 27 and carried upward into the drying chamber to the level of the partition 53' and then withdrawn from said chamber through the duct 55 at the side of the blanket of moisture 70 in the casing, thus avoiding the necessity of increasing the force of the fluid currents sufficient to destroy said blanket. The circulation created by the arrangement of intake and discharge, as just described, effects 80 the gradual drying of the pile of material within the casing.

During the operations just described the cooler medium which is supplied to the casing in contact with the material to effect 85 the drawing out of the moisture from the interior of the blocks to the exterior surfaces thereof may be supplied through the passage-way formed by the partition 54' which is substantially higher than the partition 53' 90 and hence will not interfere with the transverse circulation of the drying medium through and out of the casing over the latter partition.

There are times, during the drying operations when one side of the material may dry faster than another—therefore by manipulating the dampers which control the supply of drying fluid to the ducts 55 and 56 and to the header 39 the direction of the 100 drying fluid may be varied or its direction changed from one side to another so as to effect the drying of all parts of the mass of material equally. For example a drying or tempering fluid may be supplied transversely of the casing either over the partitions 53' or over 54' or over both, or said fluid may be supplied through the chamber 27 to the casing and discharged therefrom through one or the other of the passages 105 formed by the partitions 53' and 54'. To accomplish these results dampers 60 and 61 are provided respectively in the pipes 40 and 41 and dampers 62 and 63 are also provided in the header 39 respectively at 110 opposite sides of a discharge pipe 64, the latter pipe being preferably at the center of the header 39 so that, when the damper 61 is opened and the damper 60 closed, the blower 42 will force the fluid into the casing through the duct 56 across and around the mass of material to the duct 55 through which it will be discharged through the discharge pipe 64, it being assumed that the dampers 63, 43 are closed and the dampers 58 and 62 open although said dampers are not necessarily shown in these positions in the drawings.

Obviously the direction of flow of the fluids through the casing may be reversed by 130

reversing the positions of said dampers in the fluid ducts.

There are occasions when it is desirable suddenly to increase or decrease the temperature of the fluid that is being supplied to one side or the other of the casing through the ducts 55 and 56 just as the fluid is about to contact with the material that is being dried. To this end pipes 65 and 66 are arranged respectively adjacent the tops of the partitions 53' and 54'.

These pipes may be connected with any appropriate hot or cold source of supply such as the brine pipe 23 or the steam supply pipe 21.

It is of common knowledge that the drying medium or fluid will always follow the lines of least resistance and, owing to this tendency, it is difficult to dry all parts of a pile or mass of material uniformly but, by providing means to direct currents of the drying or tempering fluid along predetermined paths within the casing, a fluid of a predetermined or desired temperature may be directed against one section or another of the pile and, in fact, against any particular portion of the pile so as to advance or retard the drying of that particular portion.

To this end the chamber 27 below the partition or floor 25 has been divided into a plurality of compartments herein four 67, 68, 69 and 70 by partitions 71, 71 arranged vertically between the walls including the pipes 30 and 31 and each of these compartments will have independent communication with the header 39 by means of the air ducts 35, 36, 37 and 38 respectively controlled by the dampers 43.

To cooperate with the compartments 67, 68, 69 and 70 in producing currents of fluid through the drying chamber in any desired direction or angle I preferably provide at or near the top of the casing a series of compartments or ducts, herein four in number 72, 73, 74 and 75 which extend longitudinally of the drying chamber and have perforations 76 preferably in the lower walls thereof.

Communication is provided between said upper series of ducts and an appropriate fluid supply or discharging means in numerous ways but herein I have shown communication between said ducts and the blower 42, the ducts 72 and 73 being connected through branch pipes 77 and 78 and a common supply pipe 79 with the conductor 41, appropriate dampers being provided in said pipes so that the supply of air to and from one or both of the ducts 72 and 73 may be regulated. The ducts 74 and 75 are similarly connected through pipes 80 and 81 which unite in a pipe 82 communicating with the conductor 40, appropriate dampers being arranged in these pipes whereby communica-

tion may be provided between one or both of said ducts 74 and 75 with the blower 42 or with the discharge pipe 64.

A tube 83 connects the pipe 79 with the pipe 82 and a damper 84 arranged within said pipe 83 controls communication between the two.

From this arrangement is will be obvious that hot or cold or tempered fluid may be admitted through any one of the compartments 67, 68, 69 and 70 and directed across the drying chamber at substantially any angle to any one or all of the ducts 72, 73, 74 and 75 and likewise fluid may be admitted through any of the latter ducts and carried downwardly and discharged through any one of the compartments 67, 68, 69 and 70 or currents of the fluid may be discharged from any one of the aforesaid ducts or compartments into the casing and be delivered or discharged from the casing through the ducts 55 and 56 or vice versa.

At times in the operation of the drying apparatus when the drying medium is heavily laden with moisture there is a tendency for it to deposit or release, by condensation, some of its load upon the walls of the drying chamber. An increase in the temperature of said drying medium will often prevent this condensation and assist the moisture laden medium to pass off from the casing and to this end, means have been provided for tempering said drying medium or for increasing the temperature thereof as the case may be which means preferably consists of a coil of pipe 85 arranged near the roof or at least in the upper part of the apparatus, and these pipes may receive their supply of fluid from any desired source such, for example, as the steam supply pipe 21 or, if desired, said pipe 85 may be used to supply a cooler fluid to the chamber at the top to lower the temperature at that point for naturally during the drying operations where hot air is used it collects at the top of the chamber and is much hotter at that point than at the lower part but by supplying the cool air at the top the temperature throughout the casing may be kept nearer uniform.

Access to the interior of the casing may be through doors of any appropriate size or shape placed at convenient locations but herein I have shown openings for this purpose in the front wall of the casing at 86 and 87.

From the foregoing description it will be obvious that a uniform temperature may, by reason of the double walls, of the casing, be maintained in all parts of this apparatus regardless of the temperature of the atmosphere outside of the casing; that predetermined ranges of temperature may be maintained in said casing between the drying medium emanating from beneath the materials that are being dried or from the other

sources provided, or from the fluid that is being admitted at the sides of the mass of material and that substantially any combination of air currents or fluid currents may be effected within the casing to effect the drying of selected sections of the mass so that by a careful manipulation of the various instrumentalities the drying of the entire mass may be brought to completion at the same or substantially the same time without loss of material or unnecessary waste of time.

Claims:—

1. In a drying apparatus a casing having double spaced walls forming fluid containing chambers and means located within said chambers to temper fluid in said chambers. 15
2. In a drying apparatus, a casing, a series of fluid containing compartments formed within the walls of said casing and means located within said compartments independently to temper fluid in the several compartments. 20
3. In a drying apparatus, a casing having double spaced walls, the space between said walls being partitioned to form independent compartments, and means located within said compartments, for heating each of said compartments. 25
4. A drying apparatus comprising, in combination, a casing, a support for the material to be dried, means to supply a drying medium of predetermined temperature from beneath said material and means to supply counter fluid currents of predetermined temperature to said material. 30
5. A drying apparatus comprising, in combination, a casing, a support for the material to be dried, means to supply a drying medium of predetermined temperature against the material and means to direct tempered currents of fluid transversely of said casing. 40
6. A drying apparatus comprising, in combination, a casing, a support for the material to be dried, means to supply a drying medium of predetermined temperature against the material and means to direct tempered currents of fluid in either direction across said casing. 45
7. A drying apparatus comprising, in combination, a casing having a drying chamber, means to maintain a uniform temperature upon all sides of said drying chamber, means to supply drying fluid to said casing, and means to supply additional temperature to said drying fluid after the same has become laden with moisture, to assist in discharging it from said casing. 50
8. A drying apparatus comprising, in combination, a casing having a drying chamber, means to maintain a uniform temperature upon all sides of said drying chamber, regardless of prevailing atmospheric conditions outside of said casing, means to supply a drying fluid to said casing, means to supply a material tempering fluid to said casing, and means to increase the temperature of the moisture-laden drying fluid to assist in its discharge from the top of said casing. 55
9. A drying apparatus comprising, in combination, a casing having a drying chamber, means to supply a tempered drying fluid to said drying chamber, means to prevent the condensation of moisture upon the walls of said drying chamber, and means to increase the temperature of the moisture-laden drying fluid to effect its discharge from said casing. 60
10. In a drying apparatus, a casing, a perforated support for the material to be dried, and means to supply heated drying fluid to said casing through said perforated support including two headers arranged beneath said support, one upon the other, and pipes extending laterally from each of said headers, the outer ends of the pipes from one of said headers being coupled with the other ends of the pipes from the other header. 65
11. In a drying apparatus, a casing and means to supply and direct counter currents of tempered fluid to predetermined parts of said casing. 70
12. In a drying apparatus, a casing and means to direct independent currents of drying fluid to selected parts of the mass of material arranged within said casing to be dried. 75
13. In a drying apparatus, a casing, means to direct counter currents of drying fluid upward through any selected parts of said casing, and means to supply and direct tempering fluid downward through any selected parts of said casing. 80
14. In a drying apparatus, a casing and means simultaneously to supply independent currents of drying and tempering fluid to different parts of said casing. 85
15. In a drying apparatus, a casing and means simultaneously to supply independent currents of drying and tempering fluids to predetermined parts of said casing. 90
16. In a drying apparatus, a casing and means simultaneously to supply independent currents of drying and tempering fluids to different predetermined parts of said casing. 95
17. In a drying apparatus, a casing, means to supply drying fluid through the bottom of said casing and means to supply tempered fluid from selected points at the top and sides of said casing. 100
18. In a drying apparatus, a casing provided with a series of fluid ducts at the bottom thereof, a second series of fluid ducts at the top of said casing, means to supply tempered fluid to each of said fluid ducts independently of the other, and means to ef- 105
- 110
- 115
- 120
- 125

fect the passage of said fluid from any one of the lower series to any one of the upper series of ducts.

19. In a drying apparatus, a casing provided with a series of fluid ducts at the bottom thereof, a second series of fluid ducts at the top of said casing, means to supply tempered fluid to each of said fluid ducts independently of the other and means to effect the passage of fluid from the ducts of one of said series to those of the other of said series.
20. In a drying apparatus, a casing provided with a series of independent fluid ducts at the bottom thereof, a second series of independent fluid ducts at the top of said casing, means to supply tempered fluid to

each of said fluid ducts, and means to effect the passage of fluid from the ducts of one of said series to those of the other of ²⁰ said series.

21. In a drying apparatus, a casing provided with a series of independent fluid ducts at the bottom thereof, a second series of independent fluid ducts at the top of said casing, means to supply tempered fluid to each of said fluid ducts, and means to effect the passage of fluid from selected ducts of one of said series to selected ducts of the other series.

In testimony whereof, I have signed my name to this specification.

FREDERICK A. SECORD.
